SPRAY VALVE

Richard E. Hitchcock, Birmingham, Mich., assignor to
Sears, Roebuck & Co., a corporation of New York

Filed May 8, 1964, Ser. No. 79,883

Term of patent 14 years

(Cl. D91—3)

FIGURE 1 is a side elevation of a spray valve showing my new design;

FIGURE 2 is a top elevation thereof;

FIGURE 3 is a front elevation thereof;

FIGURE 4 is a bottom elevation thereof;

FIGURE 5 is a rear elevation thereof.

FIGURE 6 is a cross-sectional view thereof taken on the line 6—6 in FIGURE 1.

FIGURE 7 is a cross-sectional view thereof taken on the line 7—7 in FIGURE 1.

FIGURE 8 is a cross-sectional view thereof taken on the line 8—8 in FIGURE 1.

I claim:

The ornamental design for a spray valve, substantially as shown.
